W. S. BELLows.
RATCHET WRENCH.
APPLICATION FILED APR. 18, 1917.

1,281,484.

Patented Oct. 15, 1918.

Inventor,

Warren S. Bellows;

By *A. B. Chapman*,
attorney.

UNITED STATES PATENT OFFICE.

WARREN S. BELLOW'S, OF WORCESTER, MASSACHUSETTS.

RATCHET-WRENCH.

1,281,484.

Specification of Letters Patent. Patented Oct. 15, 1918.

Application filed April 18, 1917. Serial No. 162,915.

To all whom it may concern:

Be it known that I, WARREN S. BELLOW'S, a citizen of the United States, and a resident of Worcester, in the county of Worcester and Commonwealth of Massachusetts, have invented certain new and useful Improvements in Ratchet-Wrenches, of which the following is a full, clear, and exact specification.

This invention relates to that type of wrenches wherein a handle portion has an apertured head and a detent, and an annular peripherally toothed socket is rotatably supported in the apertured head and has its teeth engaged by the detent; and the purpose of the invention is the construction of a simple, inexpensive and durable wrench of this character, all the parts, except possibly the head, being designed to be stamped from sheet metal.

Referring to the drawings forming part of this specification, Figure 1 is an elevation of a wrench embodying my improvements. Fig. 2 is an interior view of one half of the handle portion, with the other half removed. Fig. 3 is a perspective view of the same. Fig. 4 is a perspective view of the centering block. Fig. 5 is a section through the head on the dotted line X—X, and Fig. 6 is a cross section of the line Y—Y in Fig. 1.

The body portion of the wrench is in two cupped sections 1 and 2 contacting at the edges of their rims 3, as shown in Figs. 5 and 6. The handle portion 4 of each section is substantially straight, terminating at one end in a circular head 5 having a round hole 6 concentric therewith. Within the head is located the socket member 7 having trunnions 9 turning in the holes or bearings 6, and a toothed periphery 10, the socket member having a suitable socket 11 axially through it of any desired shape and size, either square or hexagonal.

For holding the detent 12 in engagement with the teeth 10 of the socket head so that the latter will be held firmly against turning in one direction while rotating freely in the opposite direction, a block 13 is provided having a seat 14 within which an end of the detent is pivoted, as by a pin or screw 15. This block is extended to the extreme end of the handle portion 4 in order to enable it to sustain any amount of pressure

which may be communicated thereto by the 55 detent in resisting the strain exerted upon the socket member.

Moreover, the block 13 is made thick enough to lie in both body sections 1 and 2, and to fit snugly against the inner surfaces 60 of the rims 3 at numerous points, especially at the extremity of the handle and at intermediate points thereof, in order to hold the handle portions in exact alinement.

The head portions 5 are held in alinement 65 by the socket member, and the entrance of its trunnions 9 in the holes 6, so that, after screws 16 have been put through one handle section into suitably threaded holes in the other section, the wrench is complete and 70 ready for use.

First, however, a small helical spring 17 is introduced within a hole 19 drilled in the side of the detent 12 and pressing against the rim 3 thereof for yieldingly holding the 75 detent in its engagement with the toothed head.

For lightening the wrench, the block 13 is both cupped and narrowed at an intermediate portion, but I prefer to have the side 80 straight which is in line with the detent, in order more firmly to resist the thrust thereof.

What I claim is:

1. A wrench comprising two portions 85 adapted to be fastened together to compose a handle and head, the juncture being longitudinal and each portion having a rim throughout its entire edge, the rim-edges butting one against the other, each head- 90 portion having a hole concentric therewith, a socket member having trunnions rotatably supported in said holes, and a toothed periphery, a detent engaging the toothed periphery, and a block pivotally supporting 95 the detent, the block fitting between the rims of the handle portion and extended to the latter's end for withstanding the detent's operative pressure.

2. A wrench comprising two portions 100 adapted to be fastened together to compose a handle and head, the juncture being longitudinal and each portion having a rim throughout its entire edge, the rim-edges butting one against the other, each head-portion having a hole concentric therewith, a 105 socket member having hollow trunnions rotatably supported in said holes, its periph-

ery being formed with ratchet teeth, a block fitting between the rims of the handle portion and reaching to the latter's end, said block having a recess in its end adjacent the 5 socket member, a detent pivoted in said recess to rest against the latter's walls and engaging said ratchet teeth, a hole being formed in a side of the detent, and a helical spring fitting in said hole and abutting

against the rims to yieldingly press the de- 10 tent into its engagement with said teeth.

In testimony that I claim the foregoing invention, I have hereunto set my hand this 16th day of April, 1917.

WARREN S. BELLOWES.
